UNITED STATES PATENT OFFICE.

GOTTHOLD L. LANGER, OF SAN FRANCISCO, CALIFORNIA, ASSIGNOR, BY DIRECT AND MESNE ASSIGNMENTS, OF SEVENTY-FIVE ONE-HUNDREDTHS TO B. F. DURPHY, OF OAKLAND, CALIFORNIA.

PACKAGE-FORMING MACHINE.

1,052,006.

Specification of Letters Patent.

Patented Feb. 4, 1913.

Application filed May 20, 1910. Serial No. 562,530.

To all whom it may concern:

Be it known that I, GOTTHOLD L. LANGER, a citizen of the United States, residing at San Francisco, in the county of San Francisco and State of California, have invented a new and useful Package-Forming Machine, of which the following is a specification in such full and clear terms as will enable those skilled in the art to construct 10 and use the same.

This invention relates to a raisin weighing, packing and carton filling machine, and its object is to weigh definite quantities of loose raisins, place a wrapper around the 15 quantity of raisins weighed, close the wrapper over the raisins package and insert the package in an open carton. All the folding and packaging mechanisms being set in motion by the weight of the body of raisins 20 to be packed.

A further object of the invention is to produce a machine which will be operated by power merely upon the necessary quantity of material being placed upon the 25 plat- form.

Another object of the invention is to produce a machine for weighing and packaging materials which do not readily form packages of themselves, but which must be 30 pressed into a package.

Another object of the invention is to produce a machine which is capable of using one strip of paper to wrap the mass of fruit in, the paper being cut into suitable pieces 35 and passed entirely around the package, or separate sheets may be used in the machine if so desired.

Other objects of the invention will appear as the description proceeds.

In the drawings in which the same numeral of reference is applied to the same portions throughout the several views, Figure 1 is a side elevation of the machine, Fig. 2 is a plan view of the machine, Fig. 3 is 40 an end elevation of the machine looking from the right of Fig. 2. Fig. 4 is an end elevation of the machine looking from the left of Fig. 2. Fig. 5 is a vertical sectional view through the package feeding plunger 45 and weighing chamber. Fig. 6 is a side elevation of the folding mechanism showing the weighing table support "S" removed from the machine. Fig. 7 is a view in section on the line 7-7 shown in Fig. 6, a

portion of the guide flanges on the side plate 51 3 being shown.

It will be understood by those skilled in the art that it is quite difficult to weigh and package raisins or other sticky fruit of this character, for the reason that the pieces of 60 fruit become gummed to the portions of the weighing machine, or portions of the packaging machine with the result that the apparatus is quickly thrown out of commission. With this invention the fruit does 65 not come into direct contact with any part of the machine, save the feeding hopper, all other parts being covered by oiled paper which is wrapped about the mass of fruit.

The numeral 1 represents the base of the 70 machine, said base having upstanding side plates 2 and 3 secured thereto, and in which the several shafts of the machine are journaled. These two side frames are secured together by means of a square frame 4 extending across the top of the machine and in which the feeding hopper 5 is placed, said feeding hopper having a cored out portion 6 therearound to supply steam for heating the same. This feeding hopper has gates 75 7 and 8 operating in a slide 9. The gate 7 is connected to a lever 9 and the gate 8 is connected to a lever 10, said levers being pivoted at 11 and 12 respectively on the frame 4, said pivots having levers 13 and 14 80 connected therewith, a link 15 connecting the levers 13 and 14. Connected to the lever 9, below the pivot point thereof, is a bar 16 having a fork 17. This bar 16 is connected with a bell crank lever 18 which is 85 pivoted on the frame 4 at 19, said bell crank having a downwardly extending bar 20 connected thereto. The bar 20 extends down from the bell crank lever 18 through an opening in the base of the machine and it is 90 provided with a pin 21 for the purpose of opening the gates in the bottom of the feeding chute. The bar 16 operates to close said gates when a charge of fruit has been delivered to the packaging apparatus in a 95 manner to be explained later.

The weighing table 22 is supported by means of a long rod 23, which latter is in turn supported by the weighing lever 24, said weighing lever having a steel insert 25 105 to bear on the steel knife edge 26 to make the least possible friction therewith.

Extending outwardly from the machine at

an angle of about 45 degrees to the horizontal, see Fig. 1, is a weight carrying bar 24' on which the weight 27 is supported, said weight being of such size as to move 5 when the desired quantity of fruit has been placed on the weighing table. The bar 23 is pivoted to the weighing table 22, and in order that the latter may move as easily and freely as possible in the compartment in 10 which it travels, it is provided with four anti-friction wheels 28, which are placed near the center of the weighing table, and on the other two sides of the weighing table four anti-friction wheels 29 are journaled. The 15 eight wheels insuring the easiest possible movement of the weighing table, in the passage way in which it travels.

The weighing table moves from the position shown in Fig. 5 to the position indicated 20 in dotted lines below, in which latter position the body of fruit is formed into a package and has the oiled paper wrapping folded around the same.

Secured on the frames 2 and 3 are two 25 arms 30 and 31, each supporting the roll of paper 32, said roll of paper having the sheet passing under a guide roll 33, journaled in the frame 4 above the frames 2 and 3. From this point the paper 30 passes between two rolls 34 and 35 journaled on shafts 36 and 37 respectively. The roll 34 being adjusted in its bearings by means of set screws 38 which regulate the pressure of the roll 34 on the paper. One 35 of said rolls has a friction surface of cloth, rubber or the like.

The paper feed rolls are driven one complete turn at a time by means of a gear 40 in mesh with the gear 37', the cycle of operations 40 of which is to be explained later.

Journaled on the upper part of the frame 4 is a shaft 41 which is provided with a lever 42 connected to a link 43 which is raised by means of a roller 44 on the gear 45 40, said shaft 41 having two arms 45 at the free ends of which knife holders 46' are supported, said arms being held in a fixed position by means of a small shaft 46. The knife holders 46' rest on flat springs 47, said 50 flat springs serving to hold the knife in the raised position, after the paper has been cut. Attached to the knife holders 46' is a knife 48 which coöperates with a fixed knife 49 to cut off the desired amount of paper required 55 for each weighed quantity of fruit.

Journaled in the frames 2 and 3 is a shaft 50 which shaft has secured thereto a presser plate 51 which operates to press the oiled paper down on the body of the fruit and to 60 form one side of the compartment in which the mass of fruit collects on said paper. This shaft is also provided with a crank 52 connected with a link 53 which latter is connected to an arm 54 freely movable on 65 the shaft 55. The boss connected with said

arm 54 having a depending roller 56 which is held in a given position by means of the grooved cam 57 on the shaft 58. This grooved cam has a projection 59 which operates on the rotation of the shaft 58 to cause 70 the presser plate 51 to move through an arc of 90 degrees, pressing the paper down against the body of raisins on the weighing table which latter has then been forced by the weight of the fruit to its lowest position as indicated by the dotted lines on Fig. 5, the plate 51 immediately rising to its original position and being held there by the grooved cam 57.

Journaled in the side plates 2 and 3 on the opposite side of the table from the shaft 50 is a shaft 60, and loosely journaled on the shaft 60 is the folder plate 61, said plate having upstanding slotted ears 63 at the oposite edges thereof. Keyed to said shaft 85 60 are two arms 64 which have a folding point 64' to complete the operation of the folding of the paper around the ends of the package. Each arm 64 is provided with a pin 62 which extends through the slot in 90 the ear 63, the object being to permit the arms 64 to move back out of the way of the incoming sheet of paper and to hold the plate 61 against the table from which the paper is fed over the weighing compartment. The operation of this folder will be first, to press down on the paper and cause it to be pressed across the end of the package. When the plate 61 touches the top of the fruit package the arms 62 will continue 100 their rotation until they have moved slightly more than 90 degrees, and have their points 64' extending across each end of the package tucking the paper down.

Immediately below the shaft 60 there is a 105 shaft 67 also journaled in the side frames 2 and 3. This shaft carries rigidly therewith two tucking plates 68, each of which has a depending projection 69. These two tucking plates and the two tucking plates 110 64 cover about one-half of the end of the package and fold the top and bottom respectively of the paper across the ends of the body of fruit.

The frame 66, of which there is one slid- 115 able in each of the plates 2 and 3 is pro- vided with a projecting point 70 which covers the portion of the oiled paper pack- age at the right hand edges thereof, see Fig. 1, between the two plates 64 and 68. 120 This plate 66 has an upwardly extending portion 71 which coöperates with the de- pending projection 69 on the plate 68 to raise the latter into contact with the plate 64 when the plate 66 has been pushed for- 125 ward, a roller 71' lifting the arm 68 onto the portion 71.

It is to be noted that the folding mecha- nism is duplicated at each end of the formed 130 package. This plate 66 is also provided

with teeth 72 which coöperate with the teeth on the boss 73 to push forward the final tucking plate 74. The plate 74 has a projecting pin 74' which operates in a slot in an arm 73' secured on the shaft carrying the boss 73. The plate 66 is pushed forward by means of a link 75 which is pivoted thereto and which is driven by means of a crank 76 on a shaft 77, said shaft carrying the gear 40 and a small gear 78 in mesh with the larger interrupted gear 79 on the shaft 80. The shaft 80 is journaled in the plates 2 and 3 and is parallel to the shafts 77, 37 and 36. It will be observed that the gear 79 has precisely the same number of teeth as the small pinion 78, the remainder of said gear being cut-away so that upon one rotation thereof the gear 78 will be rotated one complete turn only. It will also be observed that the gear 40 has the same number of teeth as each of the gears 36' and 37', the result of which will be to drive the gears 36' and 37' one complete turn upon one rotation of the gear 40. Secured to the shaft 80 under the gear 40 is a bevel wheel 81 which is driven by means of a bevel gear 82 on the shaft 58, said shaft being journaled in boxes 83 and 84, secured to the said plate 3 extending longitudinally thereof. Immediately below the shaft 58 and parallel therewith is a shaft 85 journaled in boxes 86 and 87, said shaft having a gear 88 which has the same number of teeth as the gear 89, on the shaft 58. The shaft 85 carries a disk 90 having a pin 91 therein which is connected to a link 92, the opposite end of said link being connected at 93 to a lever 94, said lever being pivoted at 95 to the base 1 of the machine. The upper end of this lever 94 is pivotally connected to a link 96 which latter is pivotally connected at its opposite end to a plunger 97, said plunger having substantially the same cross section as the cross section of the package to be formed. This plunger 97 is movable in a slide box 98, which slide box note Fig. 5, is secured to the frame 3 at the same level as the top of the table when the package has been formed. Immediately opposite the plunger 97, the frame 2 is provided with an opening 99 through which the plunger pushes the package of fruit after the operations have been completed. Secured on the base 1 and at a short distance from the plate 2 is a side plate 100 said plate having bearings for the shafts 36 and 37, and for a shaft 101, which latter has a bearing 102 in the plate 2. This plate 100 has a bed 103 with grooves 104 and 105 therein, said grooves being for the reception of chains 106 and 107, passing over sprockets 106' and 107'. Secured to these two chains, which are parallel to each other are a plurality of carton holding boxes 108, each of said boxes having two pins 109 to hold the

flaps 110 of the carton 111 open while moving through the machine. It will also be observed that the plate 103 is cut-away at 112 to permit the depending leaf 113 of the carton 111 to extend downward during the passage of the box through the machine, the upper leaf 114 of the box pressing against the side frame 2.

Since the empty packages are to be fed continuously to the machine by means of chains 104 and 105, mechanism for moving one empty package into the place previously occupied by the filled package must be provided, and the movement must be accomplished during some time in which the plunger 97 is either stationary or moving away from the carton. Now, it will be observed that the paper feeding operation will be accomplished during the time in which the ends of the package are being folded, and before the plunger starts on its journey to press the package into the carton, therefore, the box must be moved during the period of rotation of either of the rolls 34 or 35, and since the two shafts move in opposite directions, they form convenient means for discharging the cartons in one direction or the other, as may be desired.

The shaft 101 is provided with two sprocket driving gears 106' and 107' and on its outer end it has a gear 126 which is driven from a gear 127 on the projecting end of the shaft 36, or, if desired, from the projecting end of the shaft 37, the latter gear being small enough to drive the chains 104 and 105 just the distance from center to center of two cartons, the chain 105' driving the gear 126 from the gear 127.

The shaft 58 is provided with a slidable collar 115, which collar has a clutch point 105 to connect with the clutch 116 on the boss on the pulley 117. The slidable collar is operated by means of a lever 118 having a fork extending over the collar 115, said lever being pivoted to the frame 3 and 119. The opposite end of this lever has a latch 120 pivoted thereto, the object being to throw the machine into gear when the bar 24' comes into contact therewith, and should the bar 24' accidentally pass the latch 120 it will permit the bar 24' to return to its initial position without interference.

The clutch on the collar 115 is provided with but a single point 121 which coöperates with a single point 122 on the boss of the driving pulley 117. After the clutch has made one complete turn, the clutch is disengaged by the projecting point 123 on the boss of the pulley 117 striking an oppositely placed point 124 on the lever 118 which forces the collar 115 away from the hub of the driving pulley and disengages the clutch.

In order that the bar 24 may not tip over on one side or move out of place, a slotted

4
plate 129 is secured on the knife bar 26 by means of a set screw 130 and a hole is drilled in this slotted plate to hold a ball 129' to bear on the side of the insert 25 in said bar, one of these plates being placed on each side of said bar 24. It will, of course, be understood that these balls touch the insert 25 very lightly and offer practically no resistance to the movement of the bar 24, but do prevent it from moving away from its proper position.

The cycle of operations of the machine is as follows: Starting from the position of rest shown in Fig. 1, a piece of paper having been placed under the hopper for feeding the fruit, the latter is permitted to fall on the paper, and since the paper is very pliable, the weight of the fruit is immediately carried by the table 22 of the weighing apparatus and as the weight increases to such a point as becomes sufficient to raise the weight 27, the table 22 descends to the bottom of the compartment in which it moves. As soon as the bar 24' strikes the latch 120, and fork 17 both of which operations occur at substantially the same time, the machine is thrown into gear and will start when the points 121 and 122 meet, and the supply of fruit is cut-off by the closing of the gates 7 and 8. The machine is now running to form and fold the package. The first operation which takes place is the throwing over of the roller 56 by the high place of the cam 57. This causes the presser plate 51 which operates to fold one side of the paper down over the fruit to firmly press the latter into the desired condition for insertion in the box. This presser plate is immediately returned to its initial position by the cam 57 and throughout the remainder of the cycle of operations this plate continues in the same position. Now, it will be observed that the bevel wheel 82 during this time is driving the bevel wheel 81 on the shaft 80 and the gear 79 is driving the gear 78, therefore, the slide 66 is in process of being pushed forward by the link 75. The cam 71 on said slide pushing the folder plate 68 up during the same time that the plate 51 is pressing down on the fruit, thus the package is more confined at the ends thereof. As the slide proceeds on its course it successively engages the spur gear 73 on its lower side which latter pushes the folding plates 74 one half of the distance across the ends of the package and at the same time, the points 70 on the slide have advanced one half the distance across the package from the opposite side thereof, and during this same time the teeth 65' engage the gear 65 and press the folder plates 61 and 64 down on the package. During the rotation of the shaft 77 the gear 40 is driving the gears 34 and 35 one complete turn each time. The paper is fed across the

table under the feed hopper and on the completion of the turn of the rollers 34 and 35, the roller 44 strikes the lower end of the rod 43 and causes the knife 48 to cut the paper. The spring 47 immediately returning the knife to the position shown in Fig. 1 after the paper has been cut. The continued movement of the shaft 77 returns the folding apparatus to the position indicated in Fig. 1 and as soon as the shaft 77 is stopped in that position, the gear teeth on the wheel 89 come into contact with the teeth on the wheel 88 and the latter is rotated one complete turn, the link 92 pulling the plunger against the package and forcing the fruit into the carton. The further rotation of this gear 88 returns the plunger to the position shown in Fig. 3.

It will also be observed that the packages are moved forward one box by the chain 105' which is driven by the gear 127. As soon as the plunger has been withdrawn from its travel across the weighing table, the weight causes the latter to rise and the bar 24' strikes the pin 21 and opens the feed gates allowing the fruit to again collect on the paper placed over the feed table. As soon as the shaft 58 has completed one turn, the projection 123 throws the clutch points 122 and 121 out of contact and the machine remains quiescent during the time the fruit is again collecting on the weighing table. The cycle being carried out as often as a certain weight of fruit is placed on the weighing table.

Having thus described my invention, what I claim as new and desire to secure by Letters Patent of the United States, is as follows:—

1. In a package forming machine, a balance beam, a weighing table supported by said balance beam and capable of a considerable downward movement upon the placing upon said table of a given weight of material, means to place a wrapper over said weighing table, means to feed said material on said wrapper, means to place said wrapper over the top of said material and to compress said material, folding plates to tuck in the wrapper at the ends of said body of material, and means to move the formed package off the weighing table, as set forth.

2. In a package forming machine, a balance beam, a movable table capable of a considerable downward movement upon the placing thereon of a given weight of material, means to feed a wrapper over said table, means to feed material upon said wrapper, means to fold said wrapper about the formed package of material, and means to move said formed package laterally off the weighing table, as set forth.

3. In a package forming machine, a balance beam, a movable weighing table supported by said balance beam and capable of

- a considerable downward movement upon the placing thereon of a given weight of material, means to feed a wrapper over said table, means to feed material on said wrapper, means to compress the materials on the wrapper into a formed package, means to fold the ends of the wrapper about said materials, and a plunger to slide the formed packages endwise off said weighing table, as set forth. 10
4. In a package forming machine, a balance beam, a vertically moving weighing table supported by said balance beam and capable of a considerable downward movement upon the placing thereon of a given weight of material, means to feed a wrapper over said table, means to feed said material upon said wrapper, means to compress said material into a package, plates to fold the ends of the wrapper across the ends of the package, means to deliver a carton into proximity to the weighing table, and means to slide said formed package off the weighing table into a carton, as set forth. 15
5. In a package forming machine, a balance beam, a vertically movable weighing table supported by said balance beam and capable of a considerable downward movement upon the placing thereon of a given weight of material, means to feed a wrapper over the table, means to supply said wrapper with material, whereby said table descends, means to fold said wrapper about the sides and ends of said package, means to remove said package from the weighing table, and means to restore said weighing table to its initial position after the removal of the package therefrom, as set forth. 20
6. In a package forming machine, a balance beam, a vertically movable weighing table supported by said balance beam and movable through a considerable distance upon the placing thereon of a given weight of material, rollers to feed a wrapper over the table, a knife to cut said wrapper after the same has been fed over said table, means to feed material upon said wrapper, whereupon said table moves downwardly upon receiving the requisite charge of material, means to compress said material into a package, folding plates to tuck the ends of said wrapper across the ends of said package, means to feed a supply of cartons into proximity to said weighing table, and a plunger to move said package laterally off the table into a carton, as set forth. 25
7. In a package forming machine, a balance beam, a weighing table supported by said balance beam and capable of a considerable downward movement upon the placing thereon of a given weight of material, a fixed support to which said table descends upon the placing of said given weight of material, means to place a wrapper over said material, folding plates to tuck said wrap- 30
- per across the ends of the package, and means to move the package off the table, as set forth. 70
8. In a package forming machine, a balance beam, a movable weighing table supported by said balance beam and capable of a considerable downward movement upon the placing thereon of a given weight of material, means to place a wrapper over said table, means to feed material upon said wrapper, means to fold said wrapper about the package of material, and means to move the folded package endwise off the table, as set forth. 75
9. In a package forming machine, a balance beam, a movable weighing table supported by said balance beam and capable of a considerable downward movement upon the placing thereon of a given weight of material, a fixed support upon which said weighing table rests when said given weight of material has been placed thereon, means to feed a wrapper over said table, means to feed material on said wrapper, means to fold said wrapper over said material, means to fold the ends of the wrapper across the ends of the package to be formed, and a plunger to slide the formed package endwise off said table, as set forth. 80
10. In a package forming machine, a balance beam, a vertically moving weighing table supported by said balance beam and capable of a considerable downward movement upon the placing thereon of a given weight of material, a fixed support upon which said table rests when said given weight of material has been placed thereon, means to feed a wrapper over said table, means to feed material upon said wrapper, means to compress said materials into a package, folding plates to fold the ends of the wrapper across the ends of the package, means to deliver a carton into proximity to said table, and means to slide the formed packages off the table into the cartons, as set forth. 85
11. In a package forming machine, a balance beam, a vertically moving weighing table supported by said balance beam and capable of a considerable downward movement upon the placing thereon of a given weight of material, means to feed a wrapper over said table, means to feed material on said wrapper, means to fold the wrapper across the top and ends of said package, means to move said package laterally off said table, and means to restore said table to its initial position after the removal of the package therefrom, as set forth. 90
12. In a package forming machine, a balance beam, a vertically moving weighing table supported by said balance beam and capable of a considerable downward movement upon the placing thereon of a given weight of material, rollers to feed a wrapper over said table, a knife to cut said wrapper after 100
- 130

- the same has been fed over said table, means to feed material upon said wrapper, means to compress said material into a package, plates to tuck said wrapper around said 5 body of material, means to intermittently feed a supply of cartons to the level of the table when said package has been formed, and a plunger to move said formed package endwise into one of the cartons, as set 10 forth.
13. In a package forming machine, a weighing table, a balance beam supporting said table, means to feed a sheet of wrapping across said support, a hopper adapted 15 to feed materials upon said wrapping above said support, means to completely fold said wrapping around said materials at the ends thereof while on said table, a pivoted presser plate adapted to compress said materials 20 and fold one edge of said wrapping across the same, a second pivoted presser plate, a shaft upon which said second presser plate is loosely mounted, folder plates at each end of said second presser plate and rigidly connected with the shaft upon which said presser plate is mounted, and pins passing through said pivoted plates to determine the movement of said second presser plate, as set forth.
14. In a package forming machine, a balance beam, a weighing table supported by said balance beam and capable of a considerable downward movement upon the placing thereon of a given weight of material, 25 a pair of co-acting intermittently driven rollers to feed a sheet of wrapping material over said table, means to intermittently feed materials upon the wrapper, two pivoted presser plates to fold the wrapper over the 30 top of the package and to compress said materials, folding plates to fold the free edges of the wrapper across the ends of the wrapper, and means to move the formed package endwise off the table, as set forth.
15. In a package forming machine, a balance beam, a vertically movable table supported by said balance beam and capable of a considerable downward movement upon the placing thereon of a given weight of material, 35 a pair of co-acting intermittently driven rollers to feed a wrapper over the table, means to cut the wrapper into determinate lengths, means to feed material upon said wrapper over the table, pivoted plates 40 to fold the wrapper across the top of said material and to compress it, plates to fold the free edges of the wrapping material across the ends of the package, means to retract all of said folding mechanisms to their 45 initial positions, and means to slide the formed package endwise off the table, as set forth.
16. In a package forming machine, a balance beam, a vertically movable weighing 50 table supported by said balance beam and capable of a considerable downward movement upon the placing thereon of a given weight of material, a pair of co-acting intermittently driven rollers to feed a wrapper over said table, a hopper to feed materials 55 upon said wrapper, folding devices to fold said wrapper about said material, a carrier to place a series of cartons adjacent the table, and a reciprocating plunger to push the formed package off the table into one of the 60 cartons, as set forth.
17. In a package forming machine, a vertically movable weighing table, a pair of co-acting intermittently driven rollers adapted to feed a sheet of wrapping material over 65 said table, means to cut said sheet into determinate lengths, means to feed materials upon said wrapping above said table, means to fold said wrapping around said materials, and means connected with said weighing 70 table for setting in motion said folding mechanisms, as set forth.
18. In a package forming machine, a vertically movable weighing table, a pair of co-operating rollers adapted to feed a sheet of 75 wrapping material over said table, means to feed materials upon said wrapping over said table, folding mechanisms to place said wrapping around said materials, a carrier to feed cartons into proximity to said weighing 80 table, means on said carrier to hold the ends of said cartons open, and a plunger movable across said table endwise to push the formed package off the table and into one of said cartons, as set forth.
19. In a package forming machine, a vertically movable weighing table, a weighing beam supporting said table, a rigid support upon which said table is adapted to rest when it has received a charge of materials, 85 and means to compress said materials into said package upon said table after receiving said charge, as set forth.
20. In a package forming machine, a vertically movable weighing table, a weighing 90 beam supporting said table, a rigid support upon which said table rests after it has received the charge of materials, means to define the ends of a package to be formed on said table, and means to compress the materials placed upon said table, as set forth.
21. In a package forming machine, a vertically movable weighing table, a weighing beam supporting said table, a rigid support upon which said table is adapted to rest 95 when it has received a charge of materials, and pivoted presser plates to compress the materials fed upon said table, as set forth.
22. In a package forming machine, a vertically movable weighing table, a weighing beam supporting said table, a rigid support for said table after it has received a charge 100 of materials, means to define the ends of a

- package formed on said table, and pivoted presser plates to compress the materials fed upon said table, as set forth.
23. In a package forming machine, a vertically movable weighing table, means to feed a sheet of wrapping material over said table, means to feed material over said table upon said wrapping, a movable weighing arm adapted to support said table, a fixed support upon which said table is adapted to rest when a charge of material has been fed thereto, plates adapted to fold said wrapping about said materials at the ends thereof, and means to compress said materials into a package, as set forth.
24. In a package forming machine, a movable weighing table, a weighing beam supporting said table, a rigid support upon which said table is adapted to rest when it has received a charge of materials, a pair of rollers adapted to feed a sheet of wrapping material over said table, a hopper adapted to feed materials upon said wrapping over said table, and means to compress said materials and fold said wrapping around the same, as set forth.
25. In a package forming machine, a movable weighing table, a weighing beam supporting said table, a rigid support upon which said table is adapted to rest when it has received a charge of materials, means to feed a sheet of wrapping over said table, means to cut said sheet of wrapping into determinate lengths, and means to compress said materials and fold said wrapping around the same, as set forth.
26. In a package forming machine, a movable weighing table, a weighing beam supporting said table, means to feed materials to said table, a rigid support upon which said table is adapted to rest when it has received a charge of materials, means to compress said materials upon said table, and a lever operated by said weighing beam to cut off the supply of materials to said table, as set forth.
27. In a package forming machine, a movable weighing table, a weighing beam supporting said table, a rigid support upon which said table is adapted to rest when it has received a charge of materials, means to feed a sheet of wrapping over said table, means to cut said wrapping into determinate lengths, a hopper adapted to feed materials upon said wrapping over said table, means to fold said wrapping around said materials, gates for said hopper, levers connected with said gates, and means connected with said levers whereby the weighing beam will open and close said gates in the proper sequence, as set forth.
28. In a package forming machine, a movable weighing table, a weighing beam supporting said table, a rigid support upon which said table is adapted to rest when it has received a charge of materials, means to feed a sheet of wrapping material over said table, means to cut said wrapping into determinate lengths, plates adapted to fold said wrapping about the body of material upon said table, means to feed materials on said wrapping over said table, and means whereby said weighing beam cuts off the supply of materials and sets in motion said folding means, as set forth.
29. In a package forming machine, a movable weighing table, a weighing beam supporting said table, a rigid support upon which said table is adapted to rest when it has received a charge of materials, means to feed materials on said table, means to form said materials into a package on said table, means to place a carton in proximity to said table, and a reciprocating plunger adapted to push said package off said table and into said carton, as set forth.
30. In a package folding machine, a pair of pivoted and oppositely movable V shaped plates, a pair of oppositely slidable V shaped plates, means to move the lower of said pivoted plates first, and means to move the slidable plates and other pivoted plates against the package to be folded after the first plate has reached the extent of its throw, as set forth.
31. In a package forming machine, a support, a balance beam, a weighing table carried by said balance beam and capable of moving into contact with said support upon the placing thereon of a predetermined weight of material, means to feed a wrapper over said table, a pair of pivoted plates to fold the edges of said wrapper across the top of said material, other folding devices to fold the edges of the top of the wrapper upwardly, other pivoted plates to fold the upper edges of the wrapper downwardly across the ends of the package, devices to fold the remaining edges of the wrapper across the ends of the package, means to deliver a series of cartons adjacent the table and a plunger to push the formed packages off the table into the cartons, as set forth.
32. In a package forming machine, a weighing table, means to form a package on said weighing table, a balance arm having one limb inclined at a small angle above the horizontal and having another limb inclined at a considerable angle to the horizontal, and means operated by the last mentioned limb to set in motion the package forming mechanism near the end of the throw of said balance arm, as set forth.
33. In a package forming machine, a weighing table, means to form a package on said weighing table, a balance arm having one limb inclined at a small angle above the horizontal and having an

- other limb inclined at a considerable angle to the horizontal, means operated by the last mentioned limb to set in motion the package forming mechanism near the end of the 5 throw of said balance arm, means to feed materials on said table, and means to cut off the supply of materials to the weighing table at substantially the same time the package forming mechanism is started, as set 10 forth.
34. In a package forming machine, a weighing table, means to form a package thereon, a balance arm supporting said weighing table, said arm having one limb inclined at a small angle to the horizontal and having the other limb inclined at a considerable angle to the horizontal, means operated by the last mentioned limb near the end of its 15 throw to set in motion the package forming mechanism, means operated by said last mentioned limb near the end of its throw to discontinue the supply of materials to the weighing table, and means operated by 20 said balance arm on its return to again supply the weighing table with materials, as set forth.
35. In a package forming machine, a weighing table, means to feed materials thereto means to form a package on said table, a balance arm supporting said table, said balance arm having one limb inclined at a small angle to the horizontal and having the other limb thereof inclined at a 25 considerable angle to the horizontal, a counter-weight carried by the last mentioned limb, means operated by said last mentioned limb near the end of its throw to set in motion the package forming mechanism, means operated 30 at substantially the same time by said limb to discontinue the supply of ma-

terials to said weighing table, means to move said package off said table after having been formed, and means to again supply said weighing table with materials immediately on the return of said balance arm to its initial position, as set forth. 45

36. In a package forming machine, a weighing table, mechanism to form and fold a package on said table, a power shaft having a collar thereon, a loose driving member on said shaft, a lever operated by the weighing mechanism to bring said driving member and collar into engagement to operate the forming and folding mechanism, 50 and a cam carried by said driving member to throw said member and collar out of engagement on one revolution of said shaft, as set forth.

37. In a package forming machine, a weighing table, a balance arm supporting said table, mechanism to form and fold a package on said table, a power shaft operated to drive said folding mechanism and having a slid able collar thereon, a lever and loose pulley on said shaft adjacent said collar and connected with said collar and adapted to be moved by said balance arm near the end of its throw to bring the collar and pulley into engagement, a cam operated 65 by said pulley, and an oppositely placed cam carried by said lever to disengage the collar and pulley when the power shaft has made precisely one turn, as set forth.

In testimony whereof I have hereunto set 75 my hand this 9th day of May A. D. 1910, in the presence of the two subscribed witnesses.

GOTTHOLD L. LANGER.
